Primary Examiner — Kevin K Rudzinski*Assistant Examiner* — Richard Kearney(74) *Attorney, Agent, or Firm* — John S. Artz; Dickinson Wright PLLC(57) **CLAIM**

We claim the ornamental design for a modular deck light, as shown and described.

DESCRIPTION

FIG. 1 is a perspective view of a modular deck light showing our new design;

FIG. 2 is a first end view of the modular deck light of FIG. 1;

FIG. 3 is a second end view of the modular deck light of FIG. 1;

FIG. 4 is a first side view of the modular deck light of FIG. 1;

FIG. 5 is a second side view of the modular deck light of FIG. 1;

FIG. 6 is a bottom view of the modular deck light of FIG. 1; and,

FIG. 7 is a top view of the modular deck light of FIG. 1. The broken lines in the drawings are included for the purpose of illustrating an environmental structure and form no part of the claimed design.
